UNITED STATES PATENT OFFICE.

HARRY E. NORVIEL, OF ANDERSON, INDIANA, ASSIGNOR, BY MESNE ASSIGNMENTS, TO
GENERAL MOTORS CORPORATION, OF DETROIT, MICHIGAN, A CORPORATION OF
DELAWARE.

SWITCH.

Application filed June 28, 1921. Serial No. 481,138.

To all whom it may concern:

Be it known that I, HARRY E. NORVIEL, a citizen of the United States of America, residing at Anderson, county of Madison, 5 State of Indiana, have invented certain new and useful Improvements in Switches, of which the following is a full, clear, and exact description.

This invention relates to electric switches 10 and particularly to switches for controlling the lighting and ignition circuits of automobiles.

It is an object of the invention to provide a switch which has a glass front for 15 the purpose of protecting the dial and so that the switch will compare favorably in appearance with other instruments of the automobile on the dash board such as the speedometer.

20 A further object is to provide means for securing the switch to the dash board without using screws or the like fastening into the dash board. In carrying out this object, it is a further object to provide means for clamping the switch to the dash board. In this connection, it is a further object to provide switch clamping means which can be used to secure switches to dash boards of varying thickness and of different materials, for example to a thin metal dash or to 25 a thick wooden dash.

Another object is to provide a switch having its terminals so located that wires can be attached to all of the terminals without turning the switch around or upside down.

Another object is to locate the switch terminals so that either a dimmer resistance or a vibratory short circuit indicator can be mounted on the back of the switch.

A further object is to provide a switch in which the total number of parts and number of different parts has been reduced to the minimum, thereby effecting economy in manufacture. A further object is to provide a switch in which the enclosed parts are readily accessible for repairs and adjustments.

50 Further objects and advantages of the present invention will be apparent from the following description, reference being had to the accompanying drawings, wherein a preferred embodiment of the present invention is clearly shown.

In the drawings:

Fig. 1 is a front view of the switch;

Fig. 2 is a sectional view thereof on line 2-2 of Fig. 5;

Fig. 3 is a back view thereof;

Fig. 3^a is a sectional view at A-A of Fig. 3;

Fig. 4 is a side view of the switch case;

Fig. 5 is a back view of the switch case with certain parts shown in position;

Fig. 6 is a back view of the switch case alone;

Fig. 7 is a sectional view on line 7-7 of Fig. 6;

Fig. 8 is a sectional view on line 8-8 of Fig. 5;

Fig. 9 is a back view of the switch handle;

Fig. 10 is a plan view of the switch contact blade insulating plate;

Fig. 11 is a plan view of the switch contact blade;

Fig. 12 is a plan view of the blade attaching clip;

Fig. 13 is an edge view thereof;

Fig. 14 is a plan view of the clamp ring;

Fig. 15 is a side view thereof;

Fig. 16 is a fragmentary side view thereof looking in the direction of arrow 16 in Fig. 14;

Fig. 17 is a similar view looking in the direction of arrow 17 of Fig. 14;

Fig. 18 is a side view partly in section 85 showing the switch attached to a thick dash board; and

Fig. 19 is a similar view showing the switch attached to a thin dash board.

Referring to the drawings, a switch casing 20 is provided with a flange 21 having spaced notches 22. Generally speaking the casing 20 is cup-shaped its end wall 23 having a boss 24 extending therefrom said boss having apertures 25, 26, and 27 and arcuate notches 28 and 29 and recesses 30, 31, and 32. Casing 20 is also provided with tapped holes 33, 34 and 35 and with lugs 37 and 38, the latter having a threaded connection therewith. Apertures 26 and 27 provide 90 shaft bearings.

95 Casing 20 supports dial 40, glass front or dial cover 41, gasket 42 and bezel ring 43. Ring 43 is provided with ears 44 which are bent around flange 21 of casing 20 into 100 notches 22, to hold the dial, gasket and glass 105

- in place. Dial 40 and glass 41 are each provided with apertures aligning with apertures 25, 26 and 27 of casing 20.
- A lock cylinder 50 is rotatably supported 5 within aperture 25 and is controlled by key 51. Lock cylinder 50 is provided with a flange 50^a which overlaps the hole in glass front 41 through which cylinder 50 extends. Cylinder 50 projects through locking plate 52 having a lug 53, and carries at its inner end a thrust plate 54 having portions 55 and 56 adapted to engage the lug 53. Locking plate 52 is provided with a locking lug 57 and with depressions 58 and 59 with which 10 a spring pressed dog 60 slideable in recess 32 cooperates. Locking plate 52 slides between ridges 48 and 49 extending above boss 24 of casing 20.
- Ignition switch handle 61 has a cylindrical hub 62 rotatable within aperture 27, and hub 62 carries pins 63 and is provided with a flange 64 overlapping the hole in glass front 41 through which the hub 62 projects.
- 20 Pins 63 of hub 62 support insulating washer 65 having holes 66 to receive said pins 63, and also notches 67. A contact blade 68 is supported on washer 65 by means of blade clip 69 having prongs 70 extending through holes 71 in blade 68 and into notches 67 of washer 66. The parts 69, 68 and 65 are held on hub 62 by means of screw 72 passing through these parts and screwing into hub 62. Screw 72 is insulated by 25 washer 73. The washer 65 constitutes a reversible locating member having two sets of locating provisions, namely, the diametrically located holes 66 and the diametrically located notches 67. These sets of locating provisions are in oblique angular relation. By reversing the washer with respect to the shaft or hub 62, two locations of the notches 67 with respect to hub or shaft 62 are provided. The pins 63 provide for maintaining 30 the same relation of the holes 66 to the hub 62 in either position of the locating washer 65. The contact 68 is provided with the holes 71 which are diametrically located and spaced to align with the notches 67. The clip 69 provides a connection for contact 68 with washer 65 in either a position such as shown in Fig. 11 or in an inverted position. Hence it is possible to provide for locating the contact 68 with respect to the hub or 35 shaft 62 in four positions of location. Two of these positions are apparent from Fig. 5. This construction and arrangement permit the use of the same contact piece on two adjacent shafts.
- 40 Between hub 62 and washer 65 there is located a ratchet plate 74 transverse to the shaft or hub 62, said plate having its surface corrugated to provide detents 75 adapted to be engaged by a spring pressed ball 76 located in recess 31, said plate 74 being turned by hub 62 through pins 63. Plate 74 is provided with locking notch 77 to be engaged by lug 57 when the ignition switch handle is in the off position as shown. The throw of handle 61 is limited by the lug 78 of plate 74 engaging the ends of arcuate recess 29. It will be noted that endwise movement of hub 62 is limited by the shoulder 62^a and the plate 74 which are spaced at a distance slightly greater than 75 length of aperture 27 in casing 20.
- The contact blade 68 carries fingers 80, 81, 82 and 83 for making contact in a manner to be described.
- 80 The light switch handle 61' carries parts like those carried by handle 61 and these parts and other parts cooperating therewith are designated by similar numbers but with a prime affixed. These similarly numbered parts are alike, it being apparent that parts 85 65', 68' and 69' have been differently located with respect to the hub 62' of handle 61'. The ratchet plate 74' is also located differently from plate 74. The lug 78' of plate 74', cooperates with arcuate recess 28 (Fig. 6) to limit the movement of handle 61'. Plate 74' is not provided with locking notches, but these could be provided where desired to cooperate with a locking lug on plate 52 similar to the lug 57.
- 85 Switch casing back or terminal block 90 is mounted on the casing 20 by screws 91, 92 and 92^a engaging holes 33, 34 and 35 respectively in casing 20. Block 90 supports 90 battery terminals 93 and 94, ignition terminal 95, curb light terminal 96, bright or large head light terminal 97, dim or small head light terminal 98, and tail light terminal 99. These terminals are held in place by flat headed rivets 93' to 99' inclusive respectively, (represented by dash line circles in Fig. 3) and in some instances these rivets serve as stationary switch contacts. These terminals are arranged so that the screws for 95 attaching wires thereto may be accessible to a screw driver from the top or sides of the switch, the screw driver being held substantially parallel to the back of the switch with its blade either pointing downwardly or in a substantially horizontal position. The switch need not be inverted to render the terminal screws accessible from above the switch. This arrangement of terminals however requires that the terminals in some instances be connected by straps with other 100 flat-headed rivets in order that the stationary contacts may be correctly located in circles to cooperate with blades 68 and 68' which are alike but differently located. Terminal 93 is connected by strap 100 with 105 contact rivet 100'; terminal 96 is connected by strap 101 with contact rivet 101'; terminal 97 is connected by strap 102 with contact rivet 102'; terminal 99 is connected by strap 103 with contact rivet 103'; and ter- 110
- 115
- 120
- 125
- 130

terminal 94 is connected by strap 104 with contact rivet 104'.

If handle 61 is turned to on position, blade 68 will be moved so that finger 80 touches contact 100' and finger 81 touches 95' thereby connecting the battery and ignition terminals 93 and 95. If handle 61' is turned to dim position, blade 68' will be turned so that finger 82' touches 94', finger 81' touches 99', and finger 81' touches 98', thereby connecting battery terminal 94 with tail light terminal 99 and dim light terminal 98. If handle 61' is turned to bright position, finger 83' touches 104', finger 81' touches 103', and finger 81' touches 102' thereby connecting battery terminal 94 with tail light terminal 99 and bright light terminal 97. If handle 61' is turned to curb position, finger 83' will touch 81', finger 82' will touch 99' and finger 81' will touch 101' thereby connecting battery terminal 94 with tail light terminal 99 and with curb light terminal 96.

In some installations a jumper 110 connects terminals 94 and 93. Where an overload circuit indicating device is included in the battery circuit (such as described in the patent to C. F. Kettering, No. 1,336,143 dated April 6, 1920) this device is mounted on a bracket riveted to the switch back 90 by means of rivets passing through holes 111 and 112, and the terminals of the device are connected with 94 and 93, the jumper 110 being omitted. If instead of dim or small head lights, the equipment provides only large head lights and a dimmer resistance to be inserted in the head light circuit, this resistance is connected between terminals 97 and 98. If no overload circuit indicator is mounted on the switch back, then a support for the dimmer resistance may be mounted in its place.

The manner of mounting the switch to thick and thin dash boards is shown in Figs. 14 to 19. A finishing ring 120 serving as a clamping member is located between the flange 21 of casing 20 and the dash 118. As shown in Fig. 2, ring 120 has an outwardly extending flange 121 abutting dash 118 and an inwardly extending flange abutting flange 21 of casing 20. A reversible clamping ring 123 is provided with an outwardly extending flange 124 having tapped holes 125, 126, 127 and 128, and is provided with an inwardly extending flange 129 having diametrically opposite depressions 130, 131 on the outside thereof, and diametrically opposite depressions 132, 133 on the inside thereof. Notches 134 and 135 are provided so that the ring 123 can be slipped over lugs 37 and 38 of casing 20.

To clamp the switch to thick wooden dash 118 the flange 129 of ring 123 is located nearest the dash 118 and the ring 123 is turned so that lugs 37 and 38 may engage

the depressions 132 and 133 on the inner side of flange 129. Screws 140 threading through holes 125 and 126 engage thrust ring 141 which bears against dash 118. Therefore dash 118 is clamped between rings 141 and 120.

To clamp the switch to thin dash 119, the ring 123 is reversed so that flange 124 is nearest the dash 119 and lugs 37 and 38 seat in depressions 131 and 130, respectively. Screws 140 pass through holes 127 and 128 and bear directly against dash 119.

It is therefore apparent that the dash board need be provided only with a large round opening to receive the switch. Then only two clamping screws are necessary to secure the switch upon the dash. The same clamping parts can be used to clamp the switch to thick or thin dash boards, and to wood or metal dash boards.

When the switch is located upon the dash board it presents an appearance comparing favorably with the other instruments on the dash, such as the speedometer, by reason of its glass front which protects the dial and allows the switch face to be easily cleaned without wearing off the switch dial by repeated rubbing.

In putting holes in the glass front the edges of these holes may appear unsightly. These edges are covered by the flanges 64, 64' and 50^a of the handle hubs and lock cylinder thereby eliminating accurate finishing of these holes. These flanges also assist in preventing dirt entering the switch casing.

It is also apparent that the number of different switch parts has been reduced since the movable parts of the light and ignition switches are the same with the exception of the ratchet plates which use the same punchings.

In case the lettering is applied to the dial by radium paint or other luminous paint, the glass front will protect this paint from being rubbed or clipped off.

In the off position switch handles 61 and 61' extend vertically and these handles are made thin as shown in Fig. 1, in order to keep visible a space on the dial large enough to show the name of the car. The space between the switch handle hubs and the lock is available for showing the name of the switch maker.

While the form of mechanism herein shown and described constitutes a preferred form of embodiment of the invention, it is to be understood that other forms might be adopted, all coming within the scope of the claims which follow.

What I claim is as follows:

1. In a switch, the combination with a switch shaft; of a locating member having two sets of locating provisions, the sets being in oblique angular relation; means co-

- operating with the shaft and one set of locating provisions for positioning the member with respect to the shaft in one of a plurality of locations; a contact member; and means for locating the contact in one of a plurality of positions with respect to the locating provisions of the locating member, whereby different locations of the contact with respect to the shaft may be provided.
- 10 2. In a switch, the combination with a switch shaft having pins diametrically located and projecting axially from the shaft; of a locating washer having diametrically located holes received by said pins, and having diametrically located notches in oblique angular relation to the holes; a contact; and means for connecting the contact to the washer in fixed relation to the locating notches.
- 15 3. In a switch, the combination with a switch shaft having pins diametrically located and projecting axially from the shaft; of a locating washer having diametrically located holes received by said pins, and having diametrically located notches in oblique angular relation to the holes; a contact having diametrically located holes spaced to align with said notches; and a clip having prongs adapted to project through the holes in the contact and the notches in the locating member.
- 20 4. In a switch, the combination with a switch casing adapted to project through an opening in a dash board and having a flange adapted to limit the movement of said casing in one direction through said opening, said casing having lugs projecting from the sides thereof; and a reversible clamping ring having spaced flanges, one flange adapted to engage said lugs on either side of said flange, and the other flange supporting means for clamping the switch to the dash board.
- 25 5. In a switch, the combination with a switch casing adapted to project through an opening in an instrument panel and having a flange for limiting the movement of the casing in one direction through said opening, said casing having lugs projecting dia-
- metrically from the sides thereof; of a reversible clamping ring having spaced flanges, one flange having two sets of diametrically arranged depressions each set receding from opposite sides of said flange and either set of depressions engagable by said lugs, and the other flange having tapped openings; and clamping screws for engaging the tapped openings and for pressing against an instrument panel located between the first and last mentioned flanges.
- 30 6. In a switch, the combination with a switch casing adapted to project through an opening in an instrument panel and having a flange for limiting the movement of the casing in one direction through said opening, said casing having lugs projecting diametrically from the sides thereof; of a reversible clamping ring having an inwardly extending flange and an outwardly extending flange spaced axially of the ring, the inwardly extending flange having two sets of diametrically arranged depressions, each set receding from opposite sides of said flange and either set of depressions engagable by said lugs, said inwardly extending flange having notches in order that the ring may be moved past said lugs, and the other flange having tapped openings; and clamping screws for engaging the tapped openings and for pressing against an instrument panel located between the first and last mentioned flanges.
- 35 7. In a switch, the combination with a switch handle having a rotatable hub; of a switch contact blade and means for locating and fastening said contact blade to said hub in insulated relation therewith, said means comprising an insulating locating washer drivingly positioned upon the end face of said hub, means for both locating and driving said contact blade through said washer, and a screw extending through said contact blade but insulated therefrom for securing said insulating washer and contact blade to said hub.
- 40 In testimony whereof I hereto affix my signature.
- HARRY E. NORVIEL.
